UNITED STATES PATENT OFFICE

125,917

DESIGN FOR AN END STANDARD FOR THEATER CHAIRS

Leo Jiranek, New York, N. Y., assignor to Heywood-Wakefield Company, Gardner, Mass., a corporation of Massachusetts

Application July 8, 1940, Serial No. 93,498

Term of patent 7 years

To all whom it may concern:

Be it known that I, Leo Jiranek, a citizen of the United States and a resident of New York, county of New York and State of New York, have invented a new, original, and ornamental Design for an End Standard for Theater Chairs, of which the following is a specification reference being had to the accompanying drawing, forming a part thereof. In said drawing Fig. 1 is a view in side elevation of an end standard for theater chairs showing my new design. Fig. 2 is a horizontal sectional view, on an enlarged

scale, through a part of the end standard, as taken on the line 2—2 of Fig. 1. Fig. 3 is a horizontal sectional view on the scale of Fig 2, through another part of the end standard as taken on the line 3—3 of said Fig. 1, and Fig. 4 is a view in elevation, on a scale reduced from that of Fig. 1, of that side of the standard opposite the one appearing in said Fig. 1.

I claim:

The ornamental design for an end standard for theater chairs, substantially as shown.

LEO JIRANEK.
